UNITED STATES PATENT OFFICE.

ADELBERT O. BENECKE, OF FOXBORO, MASSACHUSETTS.

ELECTROMAGNETIC DRIVE FOR SECONDARY CLOCKS OR THE LIKE.

1,070,577.

Specification of Letters Patent. Patented Aug. 19, 1913.

Application filed June 7, 1911, Serial No. 631,815. Renewed November 23, 1912. Serial No. 733,181.

To all whom it may concern:

Be it known that I, ADELBERT O. BENECKE, a citizen of the United States, residing at Foxboro, in the county of Norfolk and State 5 of Massachusetts, have invented certain new and useful Improvements in Electromagnetic Drives for Secondary Clocks or the Like, of which the following is a full, clear, and exact description, such as will enable 10 others skilled in the art to which it pertains to make, construct, and use the same, reference being had to the accompanying drawings, and to letters of reference marked thereon, forming a part of this specification.

15 My invention relates to electro-magnetic drives for secondary clocks or the like, in which an electro-magnet attracts an armature, the armature transmitting its motion to a lever, which by means of a pivoted pawl, 20 turns a ratchet wheel attached to the shaft of the minute hand. Intermediate wheels are employed for transmitting the motion from the minute hand shaft to the hour hand, as is common in clocks of the type referred to. It is obvious that the regularity 25 of the motion of the hands depends upon the regularity of the oscillations of the armature and its attached parts, therefore, the oscillations of the current before passing 30 into the electro-magnet are regulated by a standard clock, which itself has been previously regulated by a seconds pendulum. At each oscillation of the pendulum, there is 35 an arrangement by which it opens and closes the current, and thus the armature beats seconds exactly.

Heretofore, in the construction of secondary clocks of the type to which my invention relates, it has been customary to attach 40 to the armature of an electro-magnet, an arm provided with a pawl, which pawl engaged with the teeth of a ratchet wheel, so arranged that when the armature of the magnet is attracted, the pawl slides backward 45 over one tooth of the ratchet wheel, and when the armature returns to its original position, by gravity or otherwise, after the energizing current of the electro-magnet has been broken, the pawl turns the ratchet 50 wheel forward to the extent of one tooth. Such an arrangement as hitherto employed, has been found very objectionable, inasmuch as not only the armature with its attached 55 arm, has to move, but it has to carry with it, the pivoted pawl, which has to move independently around its pivot. This arrange-

ment has been found to introduce a great deal of friction, seriously interfering with the accuracy of the indications of the clock. This can readily be understood by considering what would happen in case the energizing circuit is closed for a short period of time, and the indicating mechanism should fail to operate for the reason that the pawl had not sufficient time to fall into its proper 65 position.

My invention has for its object, to provide an electro-magnetic drive for secondary clocks and the like, which is not open to the objections above referred to, and I accomplish my 70 object by so arranging stationary pins upon the electro-magnetically operated arm which is attached to the armature of the electro-magnet, that when the arm is attracted, said stationary pins will engage with the teeth 75 arranged on the peripheral surfaces of the wheels in order to impart motion thereto.

A preferred construction of a secondary 80 clock embodying my invention, is shown in the accompanying drawings, in which—

Figure 1 represents a side elevation of a secondary clock movement embodying my invention. Fig. 2 represents a front elevation of the same, the movement-supporting bracket being removed to show the mechanism. Fig. 3 represents a front view of the electro-magnetically operated arm and ratchet wheels. Fig. 4 represents a side view of the same. Figs. 5 and 6 represent front views of the ratchet wheels shown in 85 Fig. 4. Figs. 7 and 8 represent front and side views of a modified form of electro-magnetically operated arm and ratchet wheels; and Figs. 9 and 10 represent front 90 views of the ratchet wheels shown in Fig. 7. 95

Similar letters of reference refer to like parts throughout the specification and drawings.

My improved drive, (Fig. 3) comprises an electro-magnetically operated arm *a*, pivoted at *a'*, which is attached to the armature *b* of the electro-magnet *c* in any convenient manner, said arm being provided at its upper forked end with the stationary pins *d* and *e*, designed to engage with the teeth of 100 the ratchet wheels *f* and *g* respectively, the teeth of the respective ratchet wheels facing in opposite directions, as clearly illustrated in Fig. 3, so that a practically continuous 105 rotary movement will be imparted to the 110 wheels in opposite directions, when the arm *a* is moved back and forth. It will be read-

- ily seen that when the armature *b* is attracted, the pin *e* will engage with the slanting surfaces of one of the teeth of the ratchet wheels *f* and *g*, which are loosely mounted 5 on the shaft *h*, and that the pin *e* will move the wheels *f* and *g* around in the direction indicated by the arrows, to the extent of half a tooth, and that when the arm *a* is retracted by the spring *i*, the pin *d* will engage with 10 the slanting surfaces of one of the oppositely-arranged teeth of the ratchet wheels *f* and *g*, and that the pin *d* will also move the wheels *g* and *f* around in the direction indicated by the arrows, to the extent of another 15 half a tooth. Figs. 5 and 6 of the drawings, clearly illustrate that by the same motion, the ratchet wheels *f* and *g* can be driven in either direction, in accordance with the way in which the teeth are cut.
- 20 The construction shown in Figs. 3 and 4 of the drawings, enables me to employ it in secondary clocks in which one electro-magnet will operate the arm *a*, and impart to the two wheels *f* and *g*, motion in opposite 25 directions, thereby affording means for using two dial faces on opposite sides of the clock, in which case, one wheel operates the mechanism attached to one face of the clock, and the other wheel will operate the mechanism 30 attached to the other face of the clock.
- In Figs. 7 and 8 of the drawings, I have shown a modification of my invention, the arrangement of which is also designed to drive the wheels *j* and *k* in opposite directions, and in which the electro-magnetically 35 operated pivoted arm *l* is provided with four stationary pins, lettered *m*, *n*, *o* and *p* respectively, arranged on both sides of the arm as clearly illustrated in Fig. 8, said stationary pins being so arranged that they push 40 against the radial or back surfaces of the teeth of the respective ratchet wheels, in order to impart motion in opposite directions to the same, as indicated by the arrows, as distinguished from the arrangement 45 shown in Figs. 3 and 4, in which case, the stationary pins *d* and *e* engage with the slanting surfaces of the teeth of the ratchet wheels *f* and *g* respectively.
- 50 In Figs. 1 and 2 of the drawings, I have illustrated a double-faced secondary clock movement embodying the principles of my invention, in which *a* represents the driving arm attached to the armature *b* of the electro-magnet *c*. *d*, *d* and *e*, *e* respectively, are

the stationary driving pins, carried by the arm *a*, and so arranged as to engage with the radial or back surfaces of the teeth of the ratchet wheels *f* and *g*, which are attached to the shafts of the minute hand of said clock, 60 there being one minute hand shaft for each face, in any suitable manner, in order to impart motion in opposite directions to the same. *q* and *r*, and *q'* and *r'* are intermediate wheels for transmitting motion from the 65 minute shaft to the hour shaft, and *i* represents the spring which returns the arm *a* and the armature *b*, to which it is attached when the current passing through the magnet is broken.

70 Experience has demonstrated that the organization above described, is a highly efficient one, and while the device described is the preferred embodiment of my present invention, I do not care to restrict myself to 75 the exact details of construction, combination, and arrangement herein set forth, it being obvious that minor variations thereof not involving the exercise of invention may be made by any skilled mechanic, and such 80 departures from what is herein described and claimed not involving invention, I consider as within the scope and terms of my claims.

85 I claim:

1. In combination with the coöperating elements of secondary clocks and the like of the character described, drive wheels having teeth arranged on their peripheral surfaces and in opposite directions, a pivoted arm 90 electro-magnetically operated, said arm provided with engaging elements, which engage with the teeth of said wheels, in order to impart motion thereto.

2. In combination with the coöperating 95 elements of secondary clocks and the like of the character described, drive wheels having slanting teeth arranged on their peripheral surfaces and in opposite directions, a pivoted arm electro-magnetically operated, said arm 100 provided with stationary engaging elements, which engage with the slanting surfaces of the teeth of said wheels in order to impart motion thereto.

This specification signed and witnessed 105 this 3rd day of May, 1911.

ADELBERT O. BENECKE.
